TAUTENING DEVICE FOR IRONING-BOARD COVERS

Elmer M. Cobb, Santa Fe, N. Mex.

Application September 8, 1941, Serial No. 410,017

3 Claims. (Cl. 24—87)

The invention hereinafter to be described relates, in general terms to tautening devices, but in the present instance deals more specifically with an appliance by means of which the cloth cover for an ironing-board can be maintained in a smooth and unrinkled condition, over its entire working surface, several of these devices, of course, being required for each ironing-board, and distributed on the under side and along the length of the board.

Various methods and means have, from time to time been devised, seeking a solution of the problem as to the best way to keep the cover in order; but to the best of my knowledge none have qualified as being a perfectly satisfactory affair.

In my present conception, I employ a helically-wound spring, on each end of which, and integrally formed therewith, is a loop. Making connection with each of these loops is a specially designed element which I call a coupler.

The coupler has on its outer end a double claw hook the ends of which are sharply pointed so as to readily pierce the skirt portions of the ironing-board cover.

A handle member is provided with which to manipulate said coupler or device when attaching it to or detaching it from the cover.

One coupler operates on one of the aprons or skirts of the cover while the other coupler acts in the same capacity, on the opposite apron, the intervening spring causing a yieldable tension to be placed in opposite directions on the two aprons, with a consequent tautening and smoothing-out of the working surface of the cover.

To more clearly disclose the import of my invention, I have prepared the accompanying drawing in which like reference characters are employed to identify similar parts in all the different views.

In the drawing:

Fig. 1 is a transverse sectional view of an ironing-board and ironing-board cover, with one of my tautening couplers or devices mounted thereon;

Fig. 2 is a fragmentary, inverted plan view of the same;

Fig. 3 is a perspective view of my preferred design or form of coupler unit;

Figs. 4 and 5 represent, respectively, the form of the coupler wire after the two preliminary operations have been performed on it.

Referring to Fig. 1 of the drawing, an ironing-board I—B is shown in transverse sectional elevation, and mounted thereon is an ironing-

board cover C having laterally overhanging and underlying skirt or apron portions Ca by which interconnection with the tautening devices is had.

5 On the under side of the ironing-board, and spaced along its length at predetermined intervals, D, are a plurality of the tautening devices constituting my present invention.

The device embodies a helically wound spring 1 with integrally formed loops 1a on each end.

10 Interconnecting each loop 1a with one of the skirt portions Ca is a coupler unit A, made from a single strand of wire 2.

15 The ends of the wire are first sharply pointed, as shown in Fig. 4 and then bent to the double wire formation shown in Fig. 5.

Thereafter the shape contemplates a double-wire construction.

20 The coupler has a double-wire loop 2a on its inner end by which connection is made to the loop 1a, on the spring 1.

25 On the outer end of the coupler A the pointed wires 2b are separated, and each bent to constitute an element in a double-claw hook structure serving as the attaching means for securing the coupler to the skirt Ca of the cover C.

30 A handle 2c depends from the body portion of the coupler and is employed in mounting the device on the ironing-board, and demounting it therefrom.

35 In Fig. 3 the wires are twisted together, making the structure stiffer, and the two claw hooks less likely to become accidentally deformed. It also ties the two strands, forming loop 2a together, making it practically impossible to dislodge the device from the spring 1.

40 It will be further observed, by reference to Fig. 1 that, when the parts are under tension, the return bends forming the crotch portions 2d of the claw hooks 2b and the center line of the loops 2a are in substantially horizontal alignment, and that the hooks are so shaped that the tendency of the draft on the aprons is to pull them into the crotches of the hooks, thereby insuring 45 against their dislodgement from the ironing-board cover.

The operation involved in mounting or demounting the required number of tauteners on or from the ironing-board cover is extremely simple.

50 By using the handles, which are an integral part of the couplers, one of the latter is attached to one skirt. And after extending the spring and inserting the claw hooks of the other coupler into the skirt on the opposite side of the ironing-board, the work of supplying tautening means for

the cover is completed, the number of tauteners required as a set for each ironing-board being optional, but only so many as will keep all portions of the cover stretched and held in a smooth condition is necessary.

What I claim is:

1. As a new article of manufacture, a device of the class described comprising a multiple hook unit, said unit embodying a shank provided at one end with a hook for attachment to a coil spring or the like, the bill of said hook underlying one end portion of the shank, said shank having diverging limbs at its opposite end and said limbs terminating in individual anchoring and sustaining hooks, said latter hooks being in the form of return bends pointed in directions opposite to said first-named hook and overlying said limbs, whereby to provide two hooks on one side and a single hook on the other side of the shank in the manner and for the purposes described.

2. As a new article of manufacture, a device of the class described comprising a multiple hook unit, said unit embodying a shank provided at one end with a hook for attachment to a coil spring or the like, the bill of said hook underlying one end portion of the shank, said shank having di-

verging limbs at its opposite end and said limbs terminating in individual claw-like anchoring and sustaining hooks, said latter hooks being in the form of return bends pointed in directions opposite to said first-named hook and overlying said limbs, and a finger hook, the latter being attached to the bill portion of the first-named hook and underlying the intermediate portion of the shank.

5 3. A device of the class described comprising a single length of wire bent upon itself midway between its ends to provide duplicate limbs, the terminals of the free ends of the limbs being pointed, intermediate portions of the limbs being twisted about each other to form a rigid shank, said free ends at one end of the shank diverging and having the pointed terminals being fashioned into return bends defining claw-like anchoring hooks, the opposite middle bend of the wire constituting an eye, that portion inwardly of the eye being bent to form a finger hook, said finger hook underlying the twisted shank, and that portion of the limbs between the shank and finger hook being bent upon itself to form an additional eye-like hook for attachment to one end of a spring or the like.

ELMER M. COBB.
